The ornamental design for a combination plush toy and money display, as shown and described.

DESCRIPTION

FIG. 1 is a front elevational view of a first embodiment of a combination plush toy and money display, showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front elevational view of a second embodiment of the combination plush toy and money display;

FIG. 8 is a rear elevational view thereof;

FIG. 9 is a right side elevational view thereof;

FIG. 10 is a left side elevational view thereof;

FIG. 11 is a top plan view thereof;

FIG. 12 is a bottom plan view thereof;

FIG. 13 is a front elevational view of the embodiment shown in claim 1, with a broken line showing of a coin displayed in a display pocket;

FIG. 14 is a front elevational view of the embodiment shown in claim 7, with a broken line showing of a coin displayed in a display pocket; and,

FIG. 15 is a rear elevational view thereof.
